UNITED STATES PATENT OFFICE

JOSEPH F. MUSTEE, OF CLEVELAND, OHIO, ASSIGNOR OF ONE-HALF TO JOSEPH A. MUSTEE, OF CLEVELAND, OHIO

GAS BURNER

Application filed March 25, 1927. Serial No. 178,413.

This invention relates to improvements in gas burners.

The objects of this invention are to devise a gas burner so constructed and arranged that the mixture of the gas and air takes place beyond or outside of the burner itself and with which, as a result, there is eliminated the danger of flare-back and consequent extinguishment of the flame when the gas supply is reduced to a low point; to devise such a burner that is capable of producing a blue or heating flame even when the gas supply is cut down to a very low point; to provide such a burner that is comparatively simple and inexpensive to manufacture and in which the several parts can be readily assembled and also changed so as to vary the size of the flame, as may be desired.

Other objects will be apparent from the following description and claims when considered together with the accompanying drawing.

Fig. 1 is a top plan view of my improved burner; Fig. 2 is a section taken on line 2-2 of Fig. 1; Fig. 3 is a plan view of the slotted disk; and Fig. 4 is a section taken on line 4-4 of Fig. 1.

The attachment 1 has threaded connection with the gas supply pipe 2 and has its upper inner surface beveled, as indicated by reference numeral 3, so as to afford a freer flow of gas, as will appear. Upon the top of this attachment there rests a dished metal disk 4 which is slotted radially at regular intervals about its marginal portion, as at 5. This disk has a central aperture 6 through which extends a screw 7 which engages a threaded central opening in the web portion 8. This web portion has the apertures or ports 9 for passage of the gas. The screw extends also through the cap member 10 which is secured in the position shown in Fig. 2 by engagement of the head of the screw therewith. The marginal edge portion of this cap engages the edge portion of the disk and has its under face cut out so as to provide a chamber 11. The area of this chamber is increased by the bellied form of the disk 4. It will be observed that the lower edge of the cap is of less radial extent than the slits 5 so as to per-

mit the gas to be received in the chamber 11 and then deflected out through the slits. The cap 10 has the beveled corner portion 10^a so as to increase the draft of air for mixing with the gas. The gauge of metal in the disk 4 may vary according to desire, the depth of the slits, as viewed in Fig. 2, and hence the size of flame, depending upon this factor. That is, the disk 4 serves as a spacing means between the other two parts between which it is secured, and the flow of gas through the slits will vary accordingly. Regardless of the capacity of flow of gas by the particular thickness of disk, there is always had a burner opening of narrow or restricted slit form, with certain advantages incident thereto.

The ring 12 rests upon a shoulder provided upon the attachment 1 and, by means of the arms 13, supports the deflecting ring 14. This ring is slightly inclined, as shown in the drawing, and serves to deflect the jets of flame upwardly in the form of a virtual circle.

The cone member 15 is adapted to rest upon the inside bottom parts of the legs 13, the purpose of this cone member being to increase the upward draft of air for mixing with the gas as it emerges from the slits.

My present improved burner can be used with any kind of gas and it has been found to produce a highly efficient blue flame which can be lowered to an extremely low point without being extinguished. Furthermore the flame continues blue even when lowered to an extreme degree.

In my present invention, the gas mixes with the air outside of the burner and hence there is prevented the flare-back and accidental extinguishment of the flame. The narrowness of the slits serves to prevent the passage of the flame through the same to the inside of the burner; yet at the same time, the other dimensions of the slits permit sufficient flow of gas for an efficient heating flame. Also, the quantity of gas required for a given temperature is comparatively low.

Thus, with my present invention, not only is the efficiency increased, because of its extreme reliability, but there is also eliminated

the danger incident to accidental extinguishment of the flame while the gas is still turned on.

Furthermore, my particular structure is decidedly inexpensive to manufacture and, because of its simplicity and ready separability of the several parts, the combination can be varied, as may be desired. For instance, there may be employed a modified form of disk 4 in which the marginal portion thereof is inclined at a greater angle upwardly so as to project the jets of flame more in an upward direction. Or the marginal portion of the disk 4 may be formed horizontal so as to direct the jets of flame more to the side, or in other words horizontally. When the flame jets are projected upwardly to a certain degree, there may be substituted a deflecting ring of less diameter, such smaller ring being positioned at a higher level so as to intercept the same part of the jets of flame as in the other cases. That is, all of the rings of different diameters intercept the flames at the same point and the projection of the flame jets upwardly permits the use of a smaller deflecting ring so as to have a smaller diameter of flame.

Another advantage consists in the great facility with which my burner can be cleaned. Other advantages resulting from my present invention will readily suggest themselves to one who is skilled in the art to which it relates.

It is to be understood that the present disclosure is merely for purposes of illustration and that there may be devised certain modifications without departing from the spirit of my invention.

What I claim is:

1. A gas burner comprising a tubular member for feeding the gas, a disk having its extreme edge portion slitted radially and seated across the extreme outlet end of said tubular member so as to provide a burner opening through the disk, and means engaging the top marginal portion of the disk for securing the same in fixed position and occupying spaced relation to the main body thereof, said disk and securing means being constructed and arranged to provide a chamber therebetween for receiving the gas through the slitted disk and deflecting the same outwardly to the outside.

2. A gas burner comprising a tubular member for feeding the gas, a disk having its edge portion slitted radially and seated across the outlet end of the tubular member so as to provide a narrow, slit-like burner opening through the disk, and separate means arranged above the disk and engaging only the edge portion thereof for deflecting the gas therethrough radially to the outside.

3. A gas burner comprising a tubular member for feeding the gas, a disk having its extreme edge portion slitted radially and

seated in fixed position across the extreme outlet end of the tubular member so as to provide a narrow, slit-like burner opening through the disk, and separate means arranged above the disk and engaging only the edge portion thereof for deflecting the gas radially therethrough to the outside. 70

4. A gas burner comprising a tubular member for feeding the gas, a separate disk having a plurality of marginal, radially extending slits and having marginal seating engagement upon the outlet end of said tubular member so as to provide a plurality of narrow slit-like burner openings through the disk, and separate means for securing said disk in position, said securing means comprising a plate having its under side dished so as to provide a chamber above the burner openings and having engagement with the upper and outer marginal portion of said disk. 80

5. A gas burner comprising a tubular member for feeding the gas, a separate disk having a plurality of marginal, radially extending slits and having seating marginal engagement upon the outlet end of said tubular member so as to provide a plurality of narrow slit-like burner openings through the disk, and separate means for securing said disk in position, said securing means comprising a plate having its under side dished so as to provide a chamber above the burner openings, and having its marginal portions beveled above the burner openings so as to deflect the gas outwardly, the outer edge of the said securing means having engagement with the upper marginal portion of said disk. 90

6. A gas burner comprising a tubular member for feeding the gas, a separate disk having a plurality of marginal, radially extending slits and having seating engagement upon the outlet end of said tubular member so as to provide a plurality of narrow, slit-like burner openings through the disk, and separate means for securing said disk in position, said securing means comprising a plate having its under side dished so as to provide a chamber above the burner openings, and said disk having its upper surface concaved so as to supplement the said chamber, the outer edge of the said securing means having engagement with the upper marginal portion of said disk. 100

7. A gas burner comprising a tubular member for feeding the gas, a separate disk having a plurality of marginal, radially extending slits and having seating engagement upon the outlet end of said tubular member so as to provide a plurality of narrow, slit-like burner openings through the disk, and separate means for securing said disk in position, said securing means comprising a plate having its under side dished so as to provide a chamber above the burner openings, and said disk being of a substantially regular and 110

uniform concavo-convex form arranged with its concave side upward so as to supplement the said chamber, the outer edge of the said securing means having engagement with the 5 upper marginal portion of said disk.

5 In testimony whereof I affix my signature.
